UNITED STATES PATENT OFFICE

MAX WIEDECK, OF BERLIN, GERMANY

APPARATUS FOR TARGET PRACTICE

Application filed August 15, 1931, Serial No. 557,402, and in Germany December 19, 1930.

This invention relates to apparatus for target practice of the kind in which a target mounted in a working position of unstable equilibrium may be caused to topple by impact of a shot impinging thereon, the apparatus comprising means for mechanically restoring the target to its working position.

The invention has for its object to provide certain improvements in apparatus of this character as are hereinafter described and more particularly defined in the appended claims.

A preferred form of construction of the apparatus according to the invention is illustrated in the drawings, in which:

Fig. 1 illustrates a plan view,

Fig. 2 is a section according to the line II-II seen in the direction of the arrow,

Fig. 3 is a section according to the line III-III of Fig. 1 in the direction of the arrow,

Fig. 4 is a plan view of the drop catch,

Figs. 5 to 8 are sections corresponding to Fig. 2, the apparatus being in various working and intermediate positions, and

Fig. 9 is a front view.

Referring to the drawings, the apparatus is mounted on a base plate 1 provided with fixing holes 2 through which pegs or the like can be driven into the ground. The plate 1 is provided with pillars 3 which support the rectangular target carrier 5 pivotally mounted thereon as at 4. This carrier is provided on its face with upwardly bent lugs 6 and co-

operating screws 7 for securing a target 8 in position on the carrier. The target illustrated represents a marksman in a lying posture.

For higher and heavier targets which are usually nailed to a wooden lath, a clamping assembly on the back of the carrier 5 is provided comprising members 9 between which the lath can be inserted, a clamp plate 11 and clamp nuts 10. A set screw 13 mounted on a bracket 12 secured to the base plate serves as an adjustable stop for preventing the target falling backwards. Due to the low axis of rotation and the high centre of gravity of the target carrier assembly, the target in the upright position is in a state of unstable

equilibrium and has the tendency to topple forward into the position shown in Fig. 6.

Near one end of the target carrier 5 is situated a drop catch 16 pivotally mounted, by a rotatable pin 15, on a bracket 14 fixed to the base plate 1. The catch 16 is constructed as a double-armed lever and is fulcrumed at a point such that it tends to assume the position indicated in Figs. 5 and 6 with one end in contact with the base plate 1. The lever arm remote from the target carrier 5 is formed with an upwardly curved portion 17, for a purpose hereinafter to be described. The other lever arm projects under the carrier 5 and is provided at its end with a rectangular recess 18 and a slot 19 having an oblique wall 20 on the side nearest pivot 15.

Located above the recess 18 and fixed to the target carrier 5 is a guide segment 21 having an arcuate slot 22 and an eccentric outer guide surface 23 which is discontinued at 24 to form a shoulder which, when the catch 16 is raised into the positions according to Figs. 2, 7 and 8, bears against the transverse edge of the recess 18 and due to the tendency of the target to fall forward holds the drop catch 16 in the raised position, thereby locking the target carrier in the working position, i. e. where the target 8 is substantially vertical. Thus it will be appreciated that the system is in an unstable state of equilibrium and that consequently a slight percussion of the target will dislodge the drop catch 16, thereby permitting the target to fall forward. To allow of adjustment for sensitivity, there is provided a small set screw 25 mounted in a lateral projection 26 on the segment 21, which screw, in the locking position, bears against the upper side of the catch 16, as shown in Fig. 8.

The mechanism for restoring the target to the working position is shown in Fig. 1 and comprises a striking rod 27 resiliently and pivotally connected at one end to a lever 29 as at 28. This lever is fulcrumed intermediate its ends on a vertical pin 30 secured to the base plate 1 and is limited in its movement by two vertical stops 31 and 32. A spring 33, fixed at one end to a pin 34 on the base plate, holds the lever 29 against the stop 31.

The rod 27 is provided with a pin 36 which rides in the arcuate slot 22 of the segment 21. On the pin 36 is freely pivoted a pawl 35 which engages with the slot 19 when the target 5 is upright and the target carrier locked by the drop catch 16. At the pin joint at 28, the rod 27 can move vertically away from the lever 29 against the action of a spring 37 which normally retains these parts in contact. Projecting laterally from the rod 27 is a small pin 38 which moves into engagement with the upper surface of the curved portion 17 of the drop catch when the lever 29 is rotated in a clockwise direction. Such movement causes the drop catch 16 to be raised, or if this should not be possible, it causes the rod 27 to execute a yielding movement against the action of the spring 37.

The free end of the lever 29 can be connected to any suitable operating means for re-erecting the target. For instance, a rope attached to the lever may be connected with a winch arranged behind the apparatus. If necessary, several individual apparatus can be simultaneously connected to this winch.

The apparatus according to this invention operates as follows: Assuming the apparatus to be in the working position with the target locked in an upright position by the shoulder 24 bearing against the drop catch 16, the impact of a shot impinging squarely on the target in the direction of the adjusting lever 29, such as would result from a bull's eye shot, causes the shoulder 24 to become disengaged from the drop catch 16, so that both the target and drop catch are released. The forward end of the latter drops down on to the base plate 1 and the target topples forward and disappears from the view of the marksman. The arrangement of the parts in this position is shown in Fig. 6. The pin 36 carrying the pawl 35 moves, in this case, to the front end of the guide slot 22. In order to restore the target 8 to the upright position, the lever 29 is moved in the direction of the arrow shown in Fig. 1 against the action of the spring 33 into the extreme position where it bears against the stop 32 and is then released to return it to its original position against the stop 31. Figs. 6, 7 and 8 respectively show the relative positions of the parts of the apparatus at different stages of the restoring operation. The movement toward the stop 32 displaces the rod 27 longitudinally, causing the target and carrier to be raised since the pin 36 attached to the rod 27 is hard up against the forward end of the slot 22. On displacement of the rod 27, the pin 38 engages the humped portion 17 of the drop catch 16 and depresses same, so that the forward or locking end of the catch is lifted and held against the guide surface 23 of the segment 21 which rotates with the carrier 5. This position is shown in Fig. 7. Due to the eccentricity of the surface 23, the locking

end of the drop catch tends to be forced downwards again, but this tendency is resisted by the pin 38 bearing on the portion 17 of the drop catch. However, some lifting of the connecting end of the rod 27 takes place along the pivot pin 28 against the action of the spring 37, as is indicated in Fig. 7. This ensures that the drop catch 16 will spring up into locking engagement with the shoulder 24 when the rod 27 has been displaced to its extreme forward position by movement of the lever 29 to bear against the stop 32. On returning the lever 29 to its original position, i. e. the position shown in Fig. 1, the pin 38 on rod 27 is pressed down hard against the curved part 17 of the drop catch, due to the downward curve of the slot 22 assisted by the spring 37, so that the catch is still retained in engagement with the shoulder 24, thus keeping the target and carrier locked in an upright position. The freely rotatable pawl 35 does not come into action during the erection of the target.

When the apparatus is set, as shown in Fig. 2, the target may be caused to topple independently of a shot striking it, by moving the lever 29 a short distance towards the stop 32. Referring to the figure, the point of the pawl 35 is located directly near the oblique wall 20 of the slot 19 of the drop catch. If the lever 29 is now rotated towards stop 32, the pin 36 of the pawl 35 moves downwards along the arcuate slot 22 and the point of the pawl enters the slot 19, so that its back bears on the oblique wall 20 and its point bears against the vertical wall of the slot. Thus a downward pressure is exerted on the locking end of the drop catch 16, thereby disengaging the latter, by its recess 18, from the shoulder 24 of the segment 21, resulting in the movement of the parts into the position shown in Fig. 6, the target having toppled. This operation is completed without the pin 38 on the rod 27 reaching the part 17 of the drop catch. The target may be re-erected by rotating the lever 29 further, to the stop 32, to make contact between the pin 38 and part 17, the subsequent operation of the various parts being as above described.

I claim:—

1. Apparatus for target practice comprising in combination a target carrier rotatable about a fixed horizontal axis between a working and a non-working position, locking means for retaining said carrier in the working position and adapted to be rendered inoperative to permit said carrier to rotate into the non-working position and means for restoring said carrier to the working position and for rendering said locking means operative, said restoring means including an actuating member and means controlled by said member for automatically rendering said locking means inoperative.

2. Apparatus for target practice comprising

ing in combination a target carrier rotatable about a fixed horizontal axis between a working and a non-working position, locking means for retaining said carrier in the working position and adapted to be rendered inoperative to permit said carrier to rotate into the non-working position and means for restoring said carrier to the working position and for rendering said locking means operative, said restoring means including an actuating member, means controlled by said member for automatically rendering said locking means inoperative and means for preventing the motion of said carrier rotating into the non-working position being communicated to said actuating member.

3. Apparatus for target practice comprising in combination a target carrier rotatable about a fixed horizontal axis between a working and a non-working position, a ratchet member fixed to said carrier and rotatable therewith, a pawl member associated with said ratchet member but normally out of engagement therewith, a push rod operatively connected with said carrier and adapted to restore the latter to the working position, means operated by displacement of said rod for bringing said pawl member into locking engagement with said ratchet member, and means provided on said push rod adjacent said carrier for disengaging said pawl member from said ratchet member to permit said carrier rotating into the non-working position, said means being operable only during the initial displacement towards said carrier of said push rod.

4. Apparatus for target practice comprising in combination a target carrier rotatable about a fixed horizontal axis between a working and a non-working position, a ratchet member fixed to said carrier and rotatable therewith, a pawl member associated with said ratchet member but normally out of engagement therewith, a push rod operatively connected with said carrier and adapted to restore the latter to the working position, means operated by displacement of said rod for bringing said pawl member into locking engagement with said ratchet member, means provided on said push rod adjacent said carrier for disengaging said pawl member from said ratchet member to permit said carrier rotating into the non-working position, said means being operable only during the initial displacement towards said carrier of said push rod, and means for preventing the motion of said carrier rotating into the non-working position being communicated to said push rod.

5. Apparatus for target practice comprising a target, a carrier for said target rotatable about a fixed horizontal axis between a substantially vertical position and a substantially horizontal position, means for locking said carrier and target in the vertical posi-

tion said means being adapted to be rendered inoperative to permit said carrier to rotate into the horizontal position and means for restoring said carrier to the vertical position and rendering said locking means operative to retain said carrier in the vertical position, said restoring means comprising in combination a push rod having a limited longitudinal movement, a guide pin at the end of said rod adjacent said carrier, an arcuate guide slot mounted on said carrier and rotatable therewith, an abutment on said guide slot for said guide pin, a shoulder on said guide slot, an unbalanced double-armed lever fulcrumed to a fixed pivot and comprising a heavy arm and a light arm, a detent on the heavy arm of said lever, means for displacing said rod longitudinally to restore said carrier to the vertical position and means operable on displacement of said push rod for bringing said shoulder and detent into locking engagement.

6. Apparatus for target practice comprising a target, a carrier for said target rotatable about a fixed horizontal axis between a substantially vertical position and a substantially horizontal position, means for locking said carrier and target in the vertical position said means being adapted to be rendered inoperative to permit said carrier to rotate into the horizontal position and means for restoring said carrier to the vertical position and rendering said locking means operative to retain said carrier in the vertical position, said restoring means comprising in combination a push rod having a limited longitudinal movement, a guide pin at the end of said rod adjacent said carrier, an arcuate guide slot mounted on said carrier and rotatable therewith, an abutment on said guide slot for said guide pin, a shoulder on said guide slot, an unbalanced double-armed lever fulcrumed to a fixed pivot and comprising a heavy arm and a light arm, a detent on the heavy arm of said lever, means for displacing said rod longitudinally to restore said carrier to the vertical position, means operable on displacement of said push rod for bringing said shoulder and detent into locking engagement, a pawl pivoted to the guide pin on said rod and a stop on the heavier arm of said lever, said pawl being adapted to be brought into engagement with said stop on initial displacement of said rod in the locking position of the apparatus to force the detent on said lever out of engagement with the shoulder on said guide slot and thereby permit said carrier and target to rotate into the horizontal position.

7. Apparatus for target practice comprising a target carrier rotatable about a fixed horizontal axis between a substantially vertical position and a substantially horizontal position, a guide segment fixed to and rotatable with said carrier and provided with an arcuate slot and an eccentric outer guide

surface having a shoulder near the middle thereof, a horizontal push rod connected at one end to an operating lever, a pin fixed to the other end of said push rod and projecting through and slidable freely along said arcuate slot, an unbalanced double-armed lever comprising a heavy arm and a light arm disposed alongside but below said push rod with its heavy arm below and normally clear of said guide segment, said heavy arm being adapted when raised to engage with and be held by the shoulder on said guide segment when said target carrier is vertical, and means actuated by said push rod to lift said heavy arm into contact with said guide segment.

8. Apparatus for target practice comprising a target carrier rotatable about a fixed horizontal axis between a substantially vertical position and a substantially horizontal position, a guide segment fixed to and rotatable with said carrier and provided with an arcuate slot and an eccentric outer guide surface having a shoulder near the middle thereof, a horizontal push rod connected at one end to an operating lever, a pin fixed to the other end of said push rod and projecting through and slidable freely along said arcuate slot, an unbalanced double-armed lever comprising a heavy arm and a light arm disposed alongside but below said push rod with its heavy arm below and normally clear of said guide segment, said heavy arm being adapted when raised to engage with and be held by the shoulder on said guide segment when said target carrier is vertical, means actuated by said push rod to lift said heavy arm into contact with said guide segment, a pawl pivoted on said push rod and normally hanging freely downwards therefrom, a lateral extension on said heavy arm and having a slot therein, the free end of said pawl when said heavy arm is in contact with said guide segment being adapted to engage said slot to force said heavy arm and said shoulder out of engagement and thereby permit said carrier to rotate into the horizontal position.

9. Apparatus for target practice comprising a target carrier rotatable about a fixed horizontal axis between a substantially vertical position and a substantially horizontal position, a guide segment fixed to and rotatable with said carrier and provided with an arcuate slot and an eccentric outer guide surface having a shoulder near the middle thereof, a horizontal push rod connected at one end to an operating lever, a pin fixed to the other end of said push rod and projecting through and slidable freely along said arcuate slot, an unbalanced double-armed lever comprising a heavy arm and a curved light arm disposed alongside but below said push rod with its heavy arm below and normally clear of said guide segment, said

heavy arm being adapted when raised to engage with and be held by the shoulder on said guide segment when said target carrier is vertical, a projection on said push rod adapted on movement thereof towards said carrier to contact with the upper surface of said curved arm and thereby depress the same to lift said heavy arm into contact with said guide segment.

10. Apparatus for target practice comprising a target carrier rotatable between a substantially vertical position and a substantially horizontal position, a horizontal push rod, an unbalanced double-armed lever comprising a heavy arm and a light arm, a base plate having said carrier, push rod and lever mounted thereon with said lever disposed alongside but below said push rod, means connecting one end of said push rod with said carrier and adapted to provide a limited relative movement between said push rod and carrier longitudinally of said push rod, said heavy arm when raised being adapted to contact with said connecting means and form a catch for retaining said carrier in the vertical position, a projection at the other end of said push rod and adapted to contact with the lighter arm of said lever and depress the same to raise the heavy arm of said lever into its operative position, and means at the end of said push rod remote from said projection operatively engaging with said heavy arm only when the latter is raised to release said catch, thereby permitting said heavy arm to fall and said target carrier to rotate into the horizontal position.

11. In apparatus for target practice, the combination of a target carrier mounted on a fixed horizontal axis and displaceable to one side of a mean vertical position said displacement being limited by a stop and also rotatable on the other side of said mean vertical position between said position and a substantially horizontal position, a shoulder carried by said target carrier and adapted to execute the movements of the same, a freely pivoted lever adapted when said carrier is in said mean vertical position to engage said shoulder and form a catch, whereby on said carrier being moved into contact with said stop said heavy arm and shoulder are brought out of engagement to permit said carrier to rotate back through said mean vertical position into said horizontal position, and a push rod for returning said carrier to said mean vertical position and adapted for automatically raising said lever into locking engagement with said shoulder in proper time sequence to retain said target carrier in said mean vertical position.

12. In apparatus for target practice, the combination of a target carrier mounted on a fixed horizontal axis and displaceable to one side of a mean vertical position said displacement being limited by a stop and also rotat-

able on the other side of said mean vertical position between said position and a substantially horizontal position, a shoulder carried by said target carrier and adapted to execute
5 the movements of the same, a freely pivoted lever adapted when said carrier is in said mean vertical position to engage said shoulder and form a catch, whereby on said carrier being moved into contact with said
10 stop said heavy arm and shoulder are brought out of engagement to permit said carrier to rotate back through said mean vertical position into said horizontal position, a push rod for returning said carrier to said mean vertical position and adapted for automatically raising said lever into locking engagement with said shoulder in proper time sequence to retain said target carrier in said mean vertical position, a spring for returning said
15 push rod to its normal inoperative position, and means operative when said catch is made and actuated by movement of said push rod against said spring for dislodging said lever to permit said target carrier to rotate into
20 the horizontal position.

13. Apparatus as defined by claim 9, in which the push rod is connected to the operating lever by resilient means permitting of slight relative motion vertically.

30 In testimony whereof I have hereunto affixed my signature.

MAX WIEDECK.
